Primary Examiner — Leanne Was-Englehart*Assistant Examiner* — Alison Davis*(74) Attorney, Agent, or Firm* — Polsinelli PC(57) **CLAIM**

I claim the ornamental design for a television system, as shown and described.

DESCRIPTION

FIG. 1 is a front and right side perspective view of a television system, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict portions of the television system that form no part of the claimed design.

1 Claim, 4 Drawing Sheets(56)
